US00D724207S

(12) **United States Design Patent**
Sutherland et al.

(10) **Patent No.:** **US D724,207 S**
(45) **Date of Patent:** **** Mar. 10, 2015**

(54) **SURGICAL RETRCTOR**

(71) Applicant: **CardioPrecision Limited**, Glasgow (GB)

(72) Inventors: **Ying Sutherland**, Glasgow (GB); **Fraser William Havern Sutherland**, Glasgow (GB); **John Targell**, Kilmarnock (GB)

(73) Assignee: **CardioPrecision Limited**, Glasgow (GB)

(**) Term: **14 Years**

(21) Appl. No.: **29/439,486**

(22) Filed: **Dec. 11, 2012**

Related U.S. Application Data

(63) Continuation-in-part of application No. PCT/GB2011/051618, filed on Aug. 30, 2011.

(51) **LOC (10) Cl.** 24-02

(52) **U.S. Cl.**

USPC **D24/135**

(58) **Field of Classification Search**

USPC D24/133, 135, 140; 606/191; 600/201, 600/210, 214, 235

(57) **CLAIM**

The ornamental design for a surgical retractor, as shown and described.

DESCRIPTION

FIG. 1 is a top perspective view of a surgical retractor in accordance with the design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The broken lines shown in the Drawings are included for the purpose of illustrating portions of the surgical retractor that form no part of the claimed design.

1 Claim, 8 Drawing Sheets
